LUG CAP

Eric B. Kramer, Baltimore, Md., assignor to
 Crown Cork & Seal Company, Inc., Baltimore,
 Md., a corporation of New York

Application June 25, 1931, Serial No. 546,899

14 Claims. (Cl. 215—44)

The present invention relates to caps or closures, and more particularly to caps commonly known as "lug caps" for use on glass bottles and containers which have threads thereon, whereby, upon rotation of the cap, the lugs will engage the threads and securely lock the cap on the container.

An object of the invention is to provide a lug cap which has a stronger and more substantial locking lug than caps of this type which have been heretofore used, and which will, therefore, afford a greater sealing pressure against the mouth of a container.

Another object of the invention is to provide a cap having lugs which will not tend to cut or scratch the threads upon the glass container with which the lugs engage to produce a sealing pressure between the top of the cap and the mouth of the container.

A still further object of the invention is to provide a novel locking lug which may be formed with a minimum distortion of the metal, thereby avoiding mutilation of the cap decoration and weakening of the cap.

The invention seeks to produce a lug which may be formed without substantial deformation of the cap skirt, and substantially without reducing the depth of the skirt at any point. In the manufacture of lug caps it has been customary to utilize a blank which is substantially hat-shaped. The blank has a top, a depending skirt, and the free edge of the latter is formed into a flat flange extending at a right angle from the skirt. This flange is ordinarily curled upwardly to form a bead of circular form in cross section. By various operations upon this bead it has been customary to form the same into lugs of various types and the present invention relates to an improved lug which overcomes the defects of lugs heretofore used.

The conventional type of lug has been formed by pressing the bead at intervals both inwardly and upwardly, so that the lugs formed are produced not only by an inward movement upon the bead, but by an upward pressure toward the top of the cap, the latter pressure collapsing the lug along axial lines, that is, lines extending toward the top of the cap or along the axis about which the cap is rotated when applying the same to the container.

Caps in which the bead is axially collapsed have a lug with an inner edge which is relatively thin as compared to the remainder of the bead from which the lug is formed; consequently, they tend to cut or scratch the glass threads

of the container. Caps of this type are shown, for example, in the patent to Hammer, No. 1,079,238, granted November 18, 1931, and in the patent to Hammer, No. 1,440,940, granted January 2, 1923.

The present invention contemplates a distinct departure from lugs of the type shown in these patents in that the lug has an axial cross section or height which is at least equal to, if not greater than, the diameter of the bead. This increased height of the lug along its inner surface provides a broad face which will not mar or cut the glass; it also increases the strength of the lug along axial lines, i. e., in a direction away from the top, along which the pressure is exerted as the cap is applied to a container.

It has also been suggested to form lugs by pressing the bead inwardly while maintaining the cross-sectional form of the bead, but it has been found that such lugs do not have the required strength along axial lines, and do not properly engage the thread of a container. Lugs of this type are disclosed, for example, in the patent to Hammer, No. 1,440,984, granted January 2, 1923.

As distinguished from lug caps of the types above mentioned, the present invention contemplates a lug produced by radially inward pressure upon the bead, this pressure being applied so as to collapse the bead partially at least, along radial lines, or, in other words, along lines extending at a right angle to the axis about which the cap is rotated when applied to a container. The axial cross section or diameter of the bead at a right angle to the cap radii, is not reduced, but is substantially maintained so that the strength of the portion of the bead forming the lug is retained. In the preferred form of my invention this strength is increased by partially collapsing the bead along radial lines, thereby producing relatively straight vertical walls at the radially inner and outer sides of the lug.

The invention contemplates the formation of the locking lug substantially without appreciably reducing the depth of the skirt of the lugs, and, consequently, with a minimum deformation of the skirt at these points. This provides a lug having strength in the direction of sealing pressure, i. e., at a substantial angle to the top of the cap.

It has been found from practical use of lugs of this type that they do not tend to cut or scratch the glass threads of a container, since their relatively broad radially inner surfaces, which preferably have a height at least equal to the height of the remainder of the bead, afford

blunt locking portions to engage beneath the glass threads. Moreover, these radially inner surfaces are preferably straight longitudinally of each lug, or, in other words, constitute chords 5 of the arc of the skirt. Consequently, they engage beneath the glass thread of the container for a considerable portion of its length.

Since the caps are applied to glass containers so as to seal the same under considerable pressure, it is obvious that modifications of this character which guard against scratching or cutting of the thread and provide lugs of increased 10 strength are of great importance.

Another feature of the invention is the retention 15 of substantially the full length or depth of the skirt at the points where the lugs are formed. Heretofore it has been customary to shorten the skirt by a compression of the bead upwardly or substantially parallel to the axis of the cap. This 20 reduction in depth of the skirt by vertical or axial compression not only weakens the cap where the lugs are formed, but tends to destroy the ornamentation and produce an unsightly cap. The 25 confining of the inward pressure upon the bead to substantially radial lines retains substantially the full depth of the skirt, and by reducing the deformation of the skirt, prevents destruction 30 of the ornamentation and tends to minimize rusting of the cap in use, as well as tearing or cutting of the skirt in the manufacturing operation. It is preferable to exert the radial pressure 35 which causes the radial collapsing and inward movement of the bead in such a way that there is no substantial strain applied to the skirt 40 above the lug; this will avoid stretching or thinning of the metal which would result from inward movement of the skirt above the bead. This 45 is accomplished by permitting the metal of the bead to flow upwardly in a direction which tends by stretching the metal.

In the accompanying drawing there is shown a preferred embodiment of the invention, and in this drawing,

Figure 1 is a cross-sectional view.

Figure 2 is a fragmentary bottom plan view 50 taken at one of the lugs.

Figure 3 is a sectional view on the line 3-3 of Figure 2.

Figure 4 is a fragmentary sectional view 55 showing the formation of the bead before it is pressed inwardly to produce a locking lug.

Figure 5 is a cross-sectional view similar to Figure 3.

Figure 6 is a fragmentary perspective view 60 of the outside of the cap.

Figure 7 is an inside perspective showing the lug formation.

Figure 8 is a fragmentary sectional view of a 65 slightly modified form of bead, and

Figure 9 is a cross-sectional view showing the lug formed from a bead of the type illustrated in Figure 8.

Heretofore it has been customary to collapse or 70 compress the bead vertically or along the skirt, and at the same time to press the bead inwardly. Or as an alternative, it has been proposed to press the bead radially inwardly while maintaining the circular cross section. The improved cap of the present invention retains substantially 75 the full depth of the skirt by pressing the bead

radially inwardly without upward pressure or pressure along the axis about which the cap is turned when applied to a container, and at the same time the bead is partially collapsed or compressed along the same radial lines, or in 5 the direction in which it is pressed inwardly. The inward pressure is applied in such a way as to permit the metal of the bead to flow in a direction tending to slightly uncoil the bead with the result that the top surface of the lug is 10 formed by the metal of the bead and without inward movement or stretching of the metal of the skirt above the head.

This type of lug is illustrated in the accompanying drawing, wherein the cap is shown as 15 provided with a top 10, and a depending skirt 11, which is corrugated as at 12, the corrugations extending downwardly to a bead or curl, which is formed by rolling the lower edge of the skirt. The corrugations constitute means for gripping 20 the cap when applying or removing the same, and also serve to stiffen the skirt and reinforce the lugs.

The outwardly curled lower edge forms a bead 25 13, and in the present instance, the bead is formed by rolling the edge through three hundred and sixty degrees (360°), thereby producing a closed bead, best illustrated in Figs. 1 and 4. The bead is of tubular form, and preferably of 30 circular cross section. A closed bead is preferable, since it prevents cutting of the hands and provides a cap in which the edge is concealed and protected against rusting. In addition, it provides a means from which the improved lugs of 35 the present invention may be readily formed. To form the lugs the head is pressed inwardly at intervals, and it will be understood that any desired number of lugs may be provided.

The inward pressure is applied along substantially radial lines so as to produce the lugs without shortening the skirt. Moreover, the pressure is preferably applied in such a way as to collapse the lug, partially at least, along the same radial lines, thereby producing from a bead 45 of circular cross section (Figure 4) a lug of substantially oval form, as shown in Figure 5. The lug 14 (Figure 5) has a radially inner surface 15, (Figure 2), which is substantially straight longitudinally of the lug, or, in other words, circumferentially of the skirt.

The inner surface 15 merges at its ends into short connecting portions 15a where the lug joins the remainder of the bead. This lug is formed by pressing the bead inwardly without deflecting any portion of the skirt which is corrugated; in other words, only the bead is pressed inwardly. Thus there is provided the longitudinally straight radially inner surface 15, which is also substantially straight along vertical or axial lines, thereby imparting considerable 55 strength to the lug along axial lines indicated by the arrow 16 to meet the opposed pressure which is exerted against the top surface 17 of each lug.

The top surface 17 inclines outwardly from 65 the top of the radially inner surface 15 to the skirt and joins the skirt immediately below the corrugations 12. Although the top surface of the lug inclines upwardly from the radially inner surface 15 to the skirt (Figure 5), it is preferably 70 of uniform height substantially from end to end of the lug. At the ends 18 of the lug this top surface sharply merges into the inner surface 19 of the bead.

Due to the longitudinally straight or chord- 75

like formation of the radially inner surface 15, it provides a support for the thread-engaging top surface 17, and causes the latter to engage the thread through a considerable portion of the length of the latter. It has been found in practical use of the cap that a lug of this formation is a considerable improvement over a lug having a longitudinally arcuate radially inner surface, whether the latter be convex or concave.

10 As will be observed, when the bead is pressed inwardly it is compressed from the substantially circular form (Figure 4) to an oval form (Figure 5), and the inward pressure along radial lines, while reducing the radial diameter of the bead, which will be observed upon comparing Figures 4 and 5, does not appreciably reduce the diameter at a right angle to the radial diameter, or, in other words, in the direction of the height of the skirt or along the axis of the cap.

20 Thus there is provided the radially inner surface 15, which has a height or axial dimension in the direction of the arrow 16, at least equal to the axial diameter of the remainder of the bead.

25 As will be evident from a comparison of Figures 4 and 5, the radially inward movement of the bead distorts the bead from its circular form to the oval form of Figure 5, and the top surface 17 is produced in substantially its entirety by an upward flow of the metal in the bead. In other

30 words, any given point A in the bead (Figure 4), when the latter is pressed inwardly to form the lug, moves upwardly, and in the completed lug assumes the position A indicated in Figure 5. This movement is permitted in forming the lug, the skirt being held against inward movement above the lug while the metal of the bead is permitted to flow in an upward direction. The top surface of the lug is thus formed almost entirely by the bead wall without inward movement or stretching of the skirt above the bead.

35 A lug of this character is to be distinguished from a lug which is formed by pressing the bottom of the bead upwardly toward the top of the skirt. Such a lug is formed with a thin or sharp radially inner surface which tends to cut or scratch the glass thread upon the container and weaken or mutilate the same. At the same time, the full depth of the skirt is maintained at the lugs with the result that the bottom surface 20 of the lug is even with or in substantially the plane of the remainder of the bead. Consequently, since there is substantially no axial pressure or resulting deformation of the skirt in the direction of its depth, there is no tendency to mutilate any ornamentation, or to deform the skirt in such a way which would tend to tear the same in the manufacturing operation.

40 The exterior of the bead (Figure 6), although slightly compressed, due to the inward movement of the outer surface 21 of the lug and the radial collapsing of the bead where the lug is formed, remains otherwise of the same appearance as the portion of the bead between the several lugs. Hence there is provided a cap of slightly construction with no deformation of the bead in a vertical direction or axially and a smooth deformation radially.

45 The radially inner and outer surfaces 15 and 21 of the lug have portions which are substantially straight along lines parallel to the axis of the cap in the direction of the arrow 16, and thus provide stronger and more rigid supports for the top surface 17 than would continuously curved surfaces, and effectively resist deformation of the lug in use.

Referring to Figure 8, there is shown a cap having a skirt 11 and a bead 13, the latter being of circular formation and similar to the bead 13 of Figure 4, except that the bead is more completely closed by curling the free edge in excess of three hundred and sixty degrees (360°), the edge 25 being carried downwardly to substantially the bottom of the bead. This bead when pressed inwardly (Figure 9) to provide a lug of the character shown in Figure 6, produces a lug of the same general cross section, or, in other words, which is oval, as distinguished from the circular form from the remainder of the bead. But the partial collapsing or compression of the bead radially brings the surfaces of the bead within the lug substantially into contact, due to the provision of the three (3) plies 26, 27 and 28. The lug is thus of solid form, as distinguished from the hollow form of Figure 5, and the three (3) substantially vertical plies 26, 27 and 28, afford the flat inner surface 15' and the inclined 17' with a rigid supporting means to oppose deformation of the lug in the use of the cap. This form of the invention differs from that of Figure 5 primarily in the provision of a three-ply lug, as distinguished from a two-ply lug, due to the fact that the free edge of the lug in Figure 9 is extended downwardly to the bottom of the coil, as distinguished from the location of the same at the top of the coil, as in Figure 5. Moreover, the faces of the plies are substantially in contact, as distinguished from the hollow lug of Figure 5.

50 As in the form of Figures 4 and 5, the inward movement of the bead tends to cause a flow of the metal from the bead upwardly to produce the top surface of the lug, and this flow results in a tendency to slightly uncoil the bead, as will be evident from a comparison of Figures 8 and 9. In the latter figure, it will be observed that the free edge of the bead within the coil has moved upwardly from its position in Figure 8 and a point A' on the inner surface (Figure 8), in the completed lug (Figure 9) is located in a higher position or in the top surface of the lug.

55 In both forms, it will be noted that this flow of the metal in the bead does result in a slight, although practically unappreciable, lifting of the bottom surface of the bead due to the fact that there is nothing within the bead to maintain the curvature of this bottom surface during the flow. Upon comparing Figure 5 with Figure 4, it will be noted that the bottom surface of the lug (Fig. 5) is slightly above the bottom surface of the bead illustrated in Figure 4, from which the lug (Figure 5) is formed. By comparing Figure 9 with Figure 8, it will be observed that the bottom of the lug is slightly above the bottom of the bead (Figure 8) from which the lug is formed.

60 But in the two forms there is no attempt to collapse along axial lines or reduce the depth of the skirt, and this reduction in depth, although small, is necessarily incident to the flow of the metal in applying the strictly radial pressure, without attempting to stretch the metal of the skirt above the bead which would weaken the skirt and tend to tear the same in forming the lug.

65 In the two forms it will be understood that the entire lug is formed solely from the bead substantially without utilizing any portion of the skirt above the bead. Thereby there is avoided weakening of the metal in the skirt which would result from thinning or stretching the same in an effort to form the top of the lug by deflecting inwardly the skirt above the bead.

70 In both forms of lugs there are provided longi-

tudinally straight inner chord-like surfaces 15, 15', which support the top thread engaging surfaces 17, 17', and permit the latter to engage the thread of the container throughout a substantial portion of its length, which is not possible when the lugs are provided with longitudinally convex radially inner surfaces. Moreover, this formation increases the strength of the lug by supplying a more extended support against downward pressure applied against the top surface of the lug along the line of arrow 16. When the hollow lug formation of Figure 5 is somewhat preferable, due to the fact that it provides a resilient or cushioning effect when the cap is applied to the container, this cushioning effect is not essential with a lug of the character disclosed, and the form of Figures 8 and 9 is satisfactory. Actual use of the cap shows that it may be applied readily with a positive gripping effect, and without cutting of the glass thread. Although the cap may be readily removed, the lug is of such strength that it provides a tight seal between the liner and lip of the container without unduly deforming the lug.

25 Although the invention has been described in detail, it will be understood that it is not limited to all features set forth in the drawing and in the foregoing description, and that modifications of the several forms described may be made without departing from the invention.

I claim:—

1. A metal cap for containers comprising a top having a depending skirt provided at its lower edge with a hollow bead, said bead being pressed radially inwardly at intervals and partially collapsed in the same direction to form lugs, each having a substantially longitudinally straight radially inner surface approximately equal in height to the diameter of the remainder of the bead.
2. A metal cap for containers comprising a top having a depending skirt provided at its lower edge with a hollow bead, said bead being pressed radially inwardly at intervals and partially collapsed in the same direction to form lugs, the inner surface of each lug being substantially equal in height to the diameter of the remainder of the bead, and being substantially straight along lines forming a chord of the arc of the skirt.
3. A metal cap for containers comprising a top having a depending skirt provided at its lower edge with a tubular bead, said bead being pressed inwardly at intervals to form hollow lugs, each having an inner surface in height approximately equal in the diameter of the remainder of the bead, said surface being straight along lines forming chords of the arc of the skirt, the bottoms of said lugs being in substantially the plane of the bottom of the remainder of the bead whereby the skirt is of uniform depth throughout.
4. A metal cap for containers comprising a top having a depending skirt and provided at its lower edge with a bead, said bead being pressed inwardly at intervals to form lugs having bottoms in substantially the plane of the bottom of the remainder of the bead, each lug having an inner surface which is substantially straight, circumferentially of the skirt and which has a height at least substantially equal to the diameter of the remainder of the bead.
5. A metal cap for containers comprising a top having a depending skirt and provided at its lower edge with a bead, said bead being pressed inwardly along substantially radial lines at intervals to form lugs having bottoms in substan-

tially the plane of the bottom of the remainder of the bead, each lug having an inner surface which is longitudinally straight circumferentially of the skirt.

6. A metal cap for containers comprising a top having a depending skirt and provided at its lower edge with a bead, said bead being pressed inwardly along substantially radial lines at intervals to form lugs having bottoms in substantially the plane of the bottom of the remainder of the bead, each lug having an inner surface which is longitudinally straight circumferentially of the skirt along a line constituting a chord thereof, the part of the bead forming the lug being radially narrower than the remainder of the bead and at least the height of the bead.

7. A metal cap for containers comprising a top having a dependent skirt and provided at its lower edge with a bead, said bead being pressed inwardly at intervals to form hollow lugs having bottoms in substantially the plane of the bottom of the remainder of the bead, each lug having an inner surface which is straight longitudinally of the lug and circumferentially of the skirt, the part of the bead forming the lug being radially narrower than the remainder of the bead and approximately the height of the bead.

8. A metal cap for containers comprising a top having a depending skirt and provided at its lower edge with a bead, said bead being pressed inwardly at intervals to form lugs having bottoms in substantially the plane of the bottom of the remainder of the bead, each lug having an inner surface which is straight longitudinally of the lug and circumferentially of the skirt, the top of each lug being rounded convexly toward the cap top longitudinally of the lug.

9. A metal cap for containers having a depending skirt provided at its lower edge with a bead pressed inwardly at intervals to form locking lugs, each lug having an inner surface which is straight longitudinally of the lug and circumferentially of the skirt and which in height is approximately equal to the diameter of the remainder of the bead.

10. A metal cap for containers having a depending skirt provided at its lower edge with a tubular bead pressed radially inwardly and compressed in the same direction at intervals to form locking lugs, each lug having an inner surface which is straight longitudinally of the lug and circumferentially of the skirt and which in height is approximately equal to the diameter of the remainder of the bead.

11. A metal cap for containers having a depending skirt provided at its lower edge with a bead pressed inwardly at intervals to form locking lugs, each lug having a straight inner surface circumferentially of the skirt, the portion of the bead in each lug being of greater diameter axially of the cap than radially.

12. A metal cap for containers comprising a top having a depending skirt provided at its lower edge with a bead of substantially circular form, said bead being pressed inwardly and partially flattened along substantially radial lines at intervals to form lugs having a substantially longitudinally straight inner face and a substantially oval cross-section of less diameter radially than the remainder of the bead and axially having a diameter about equal to the remainder of the bead.

13. A metal cap for containers comprising a top having a depending skirt provided at its lower edge with a bead of substantially circular form, said bead being pressed inwardly and partially

flattened along substantially radial lines at intervals to form lugs having a substantially longitudinally straight inner face and a substantially oval cross-section of less diameter radially than the remainder of the bead and axially of about the same diameter as the remainder of the bead, each lug having its bottom surface in substantially the plane of the bottom of the remainder of the bead.

5

- 10 14. A metal cap for containers comprising a top having a depending skirt provided at its lower

edge with a bead of substantially circular form, said bead being pressed inwardly and partially flattened along substantially radial lines at intervals to form lugs having a substantially longitudinally straight inner face and a substantially oval cross-section of less diameter radially than the diameter of the bead and axially at least equal to the remainder of the bead, each lug having a radially inner surface about equal in height to the diameter of the remainder of the bead. 10

ERIC B. KRAMER.
